JOHN J. EGAN, OF BOSTON, MASSACHUSETTS, ASSIGNOR TO WILLIAM L. COLLINS, OF BOSTON, MASSACHUSETTS.

ELECTRIC SWITCH.

Application filed March 25, 1926. Serial No. 97,272.

The object of this invention is the construction of means for automatically cutting out electric current from an instrumentality when the latter is put into a position not 5 normal thereto; and particularly to an electrically heated flat-iron when the same is turned upon its heel. The means which I have found to give the best results is the force of gravity acting upon a loosely hinged 10 contact member, whereby during the normal operative position of the iron, the contact members are in touch, and thereby switches current to the heater element, but when the iron is stood upon its heel, the first 15 contact member swings out of touch, and the current is cut out.

In the drawings forming part of this specification, Fig. 1 is a side view of a flat-iron stood upon its heel and thereby having 20 the current cut out therefrom, the view being partially in section. Fig. 2 is a side view of the gravity switch alone and with its contact members in touch. Fig. 3 is a top view of the same. Fig. 4 is a perspective 25 view on a somewhat magnified scale showing the contact members out of touch.

When this gravity switch is applied to an electrically heated flat-iron, as 1, which is provided with feet 2 at its heel upon which 30 to be stood when not being used, the iron body 3 is recessed, preferably at its heel-end, and within this recess 4 is located the switch.

The switch consists of an elbow 5 suitably fastened in place, as by a screw 6, but insulated from the body 3, and carrying two terminals 7 spaced from each other and each consisting of a small block of compressed carbon. Each terminal is held in place by a small bolt 9 insulated from the elbow 5 and provided with two nuts 10 both for attaching the block thereto and for holding a lead wire in the circuit of the heater element.

At the outer edge of the elbow 5 are two 45 eyes 11 between which is loosely pivoted an eye 12 of a plate 13 fastened to an elongated block 14, which is also composed of compressed carbon or graphite, and is weighted by a metal block 15 attached thereto by 50 screws 16.

When the flat-iron is being used, the elongated

block 14 rests against the two terminals 7 and thereby completes the circuit through them, as shown in Fig. 2; but when the iron is stood on end, as shown in Fig. 55 1, the elongated block 14 swings away from the terminals 7 and the circuit is broken.

I prefer the compressed graphite or carbon for the parts 7 and 14 because of the elimination of sparking, and also because 60 there can be no corrosion of the surfaces, as occurs with metals.

It should be noted that the contact block 14 is not directly beneath the pivotal axis 11, 12, but is so far away from a vertical 65 plane in said axis as to bring the centre of gravity of the block at an angle in a plane lying in this axis of approximately forty-five degrees. Thus disposed, the action of gravity upon the block forces it against the 70 contacts 7 with greatly increased pressure as compared with a block suspended from a point in the same vertical plane with the outer surfaces of the contacts. This is very 75 important, for were the pivot located as last described, the reciprocation of the flat-iron during use would act to frequently swing the block 14 away from the contacts 7 and cause injurious sparking.

What I claim as my invention is:

In a gravity switch for electric flat irons having a heel rest, the combination with the flat iron, of a vertical plate attached to the flat iron, two spaced insulated contacts attached to said plate, a second plate having 80 an angularly disposed flange hinged at its edge to the upper edge of said vertical plate, and a single elongated contact member attached to the second plate to normally rest against said spaced contacts, the latter being 85 terminals in the heater circuit of the flat iron, whereby the center of gravity of the second plate and its contact member is materially beyond a vertical plane through said hinge, and gravity cannot break the circuit 90 until the flat iron is tipped nearly upon its heel rest.

In testimony that I claim the foregoing invention, I have hereunto set by hand this 24th day of March, 1926.

JOHN J. EGAN.
